UNITED STATES PATENT OFFICE

GEORGE ASHTON, OF GEISELGASTEIG, NEAR MUNICH, AND GOTTFRIED FREI, OF MUNICH, GERMANY, ASSIGNORS TO ARNOLD HAEFELI, OF MUNICH, GERMANY

CARBURETOR

Original application filed August 15, 1927, Serial No. 213,022, and in Germany April 16, 1927. Divided and this application filed May 28, 1929. Serial No. 366,682.

This invention relates to jet carburetors, and has for its object to provide readily adjustable means to control the jet and air by means of a horizontally disposed rotatable 5 piston device, and is a division of U. S. patent application Serial No. 213,022, filed August 15, 1927 which matured to Patent 1,778,444 issued Oct. 14, 1930.

The invention consists of a carburetor of 10 the jet type in which the jets are arranged transversely of the mixture outlet to which the mixture supply pipe or engine intake is connected, the air inlet to the carburetor being controlled by a rotatable member parallel 15 to the jets having controlling edge inclined to the horizontally directed slot above the jet orifices, and thereby upon rotation gradually regulating the passage of mixture from the slot to the intake.

20 Referring to the drawings in which like parts are similarly designated—

Figure 1 is a vertical section of a carburetor embodying the invention.

Fig. 2 is a cross-section on line 2—2 of 25 Fig. 1.

Fig. 3 is a view of the rotatable member, and

Fig. 4 is a section on the line 4—4 of Fig. 1.

The float chamber 2 contains the usual 30 float 1, and fuel inlet 3 controlled by the float. The liquid fuel in chamber 2 passes from the float chamber through a hole 4 into a narrow vertical chamber or slot 5, closed at its top at the liquid level by a horizontally disposed rotatable jet tube 6 in the bottom of 35 which are disposed several jet orifices 7, and directly above them in the upper wall of the tube 6 is a longitudinal slot 8.

This slot 8 lies in the path of the carbureting air entering an opening 10 extending along the slot 8, and the mixture is controlled by a rotary throttle valve 9". Both the valve 9" and tube 6 seat in simple bores in the body or casing of the carburetor. The 45 valve 9" has a longitudinal passage 11 there-through for the passage of the mixture to the engine in-take connection 12.

The edge of the passage 11 through the valve proximate the slot 8 of the jet tube 6 50 has an inclined lip 20, either straight or

slightly curved, and the valve may be angularly displaced in the direction of the arrow 21, Fig. 2, to admit more or less mixture to the engine, and the inclined edge 20 will very gradually control the mixture.

A screw 13 cooperates with a recess 22 in the valve to adjust the valve 9" to correspond to the idle running of the engine.

We claim—

1. The combination with a carburetor body, 60 a float chamber and a narrow slot-like chamber into which the float chamber discharges; of a horizontal tube closing the top of the latter chamber the lower wall of which tube has jet openings at the liquid level and whose upper wall has a slot over said openings, said tube being mounted in a bore of the carburetor body, a horizontal air inlet opening at about the level of said slot, a second, larger bore in the carburetor body, a rotatable throttle valve 70 in the bore past said opening and having a horizontal passage therethrough, said passage proximate the slot in the tube, the valve passage having a controlling edge inclined to the axis of the valve to gradually control the mixture formation, and adjustable means to limit the rotation of the valve for idle engine running.

2. The combination with a carburetor body, 80 a float chamber, and a narrow vertical slot-like chamber into which the float chamber discharges, and an air intake extending above transversely across said vertical chamber; of a horizontal tube closing the top of the vertical chamber, the lower wall of the tube having holes communicating with the vertical chamber and whose upper wall has a slot discharging into the intake, a rotary cylinder valve proximate the tube and parallel therewith and having a transverse passage there-through for registering with the intake and provided with a bevel edge controlling the intake air to variable distances across the slot in the upper wall of said tube without throttling the slot.

In testimony that we claim the foregoing as our invention, we have signed our names hereto.

GEORGE ASHTON.
GOTTFRIED FREI.
